UNITED STATES PATENT OFFICE.

NICHOLAS ALBRECHT, OF PHILADELPHIA, PENNSYLVANIA, ASSIGNOR TO FRED PEARSON & CO., OF PHILADELPHIA, PENNSYLVANIA.

DESIGN FOR A CUT PILE FABRIC.

48,768.

Specification for Design.

Patented Mar. 28, 1916.

Application filed January 31, 1916. Serial No. 75,452. Term of patent 3½ years.

To all whom it may concern:

Be it known that I, NICHOLAS ALBRECHT, a citizen of the United States, residing at Philadelphia, in the county of Philadelphia and State of Pennsylvania, have invented a new, original, and ornamental Design for Cut Pile Fabrics, of which the following is a specification, reference being had to the accompanying drawing, forming a part thereof.

The figure is a plan view of a portion of a cut pile fabric, showing my new design. I claim:

The ornamental design for a cut pile fabric, as shown.

NICHOLAS ALBRECHT.

Witnesses:

JOS. KAUFMAN, Jr.,
JNO. E. CARSON.
